UNITED STATES PATENT OFFICE

LEONARD D. WHALEY, OF LOS ANGELES, CALIFORNIA, ASSIGNOR, BY MESNE ASSIGNMENTS, TO TAYLOR-TRAVERS CORPORATION, LTD., OF LOS ANGELES, CALIFORNIA, A CORPORATION OF CALIFORNIA

DESIGN FOR A CASING FOR A RADIO CIRCUIT-CONTROLLING APPARATUS

Application filed September 30, 1929. Serial No. 32,896. Term of patent 3½ years.

To all whom it may concern:

Be it known that I, LEONARD D. WHALEY, a citizen of the United States, residing at Los Angeles, in the county of Los Angeles and State of California, have invented a new, original and ornamental Design for a Casing for a Radio Circuit-Controlling Apparatus, of which the following is a specification, reference being had to the accompanying drawing, forming part thereof.

The figure is a plan view of a casing for a radio circuit-controlling apparatus showing my new design.

I claim:

The ornamental design for a casing for a radio circuit controlling apparatus, as shown.

LEONARD D. WHALEY.
